TICKET FOR MARKING DELICATE FABRICS.

Application filed June 14, 1926, Serial No. 116,011, and in Germany December 5, 1925.

This invention relates to tickets or labels adapted to be attached to fabrics or other merchandise of various kinds, and the object of this invention is to provide for a ticket which can be attached without any risk even to the most sensitive materials and to the finest and most delicate woven fabrics.

The tickets hitherto known, such as pin-tickets, having pins to be pierced through the fabric to be marked, or the so-called clip-on tickets having a clip with one or more prongs thereon, are very unsuited for marking the delicate woven fabrics and sensitive materials which are coming more and more into use, as the pins or the prongs destroy the meshes of the fabric and cut through the threads thereof even when attaching the tickets to the goods or when removing them from the fabrics.

Experiments made with the intention of avoiding the cause of the damage to the goods by using, instead of pins or prongs, a wire-bow for attaching the ticket to the fabric were a failure, as the wire-bow, as a consequence of its elasticity, springs back immediately after the fingers of the operator cease to press against it, and, therefore, a solid clamping action can not be obtained by the means mentioned before. Such ticket does not hold firmly to said delicate products but will soon be lost.

In contradistinction thereto the object of the present invention is a ticket which can be attached without any risk to the goods to even the most delicate, the finest and most sensitive fabrics and the like, and which at the same time holds firmly to these delicate products, while when it is removed from the goods, does not even then cause any damage thereto even if it be removed in a hurried manner and without particular care.

According to the present invention the means for attaching the ticket to the materials or fabrics to be marked is formed by a stirrup of wire having two parallel or approximately parallel wire-limbs rigidly secured to the ticket and extending over the upper edge of the ticket, and a wire portion connecting said limbs, said connecting portion forming one or two tongues which are bent or bendable toward the rear side of the ticket in such a manner that the tongue or tongues and the before-said limbs are forming a hook with which the ticket can be

pushed over the upper edge of the fabric, said tongue or tongues being furthermore so formed or constructed that they can be pushed, together with the fabric, from a plane disposed behind the parallel or approximately parallel wire-limbs, between or past said limbs, forwards to a plane disposed before said limbs, and can further be bent down together with said limbs over the upper edge of the ticket. The points provided on the ends of the wire stirrup are intended at the same time to be embedded in the material of the ticket or in any case lie in such a way that they are located between the front and the back of the ticket so as to prevent any damage to the goods or the hands of the assistant.

Two different forms of tickets embodying this invention and showing the main features of same are illustrated in the accompanying drawings:

Figure 1 shows one constructional form in front elevation, and Figure 2 is a section on the line 2-2 of Figure 1.

Figure 3 shows in a section on the line 3-3 of Figure 1 a phase in the application of the ticket to the goods, and Figure 4 shows, looking towards the back of the ticket, the ticket attached to the fabric.

Figures 5 and 6 show in front and side elevation respectively the second constructional form.

In the constructional form shown in Figures 1 to 4, 1 indicates the ticket, to which a wire stirrup is rigidly secured, having the two perfectly or approximately parallel limbs 3 and 4 directed at right angles to the upper edge 2 of the ticket, and extending or projecting over it and between the said limbs 3 and 4 a tongue 5 connecting said limbs. In the constructional form illustrated, the stirrup terminates in points 6 (see Figure 2) which lie sunk in the material of the ticket.

The tongue 5 lying between the two limbs 3 and 4 of the wire is either bent towards the back of the ticket in the manner shown in Figure 2 or can be bent towards it, so forming a hook whereby the ticket can be placed over the upper edge of the fabric or the like. The tongue 5 is so arranged that after the hook formed by the tongue 5 and the limbs 3 and 4 of the wire has been pushed over the upper edge of the fabric 7 it can be bent together with the latter be-

tween the limbs 3 and 4 of the wire forwards, that is to say, into the position shown in Figure 3.

In order to completely affix the ticket to the goods it is only necessary to bend back the limbs 3 and 4 of the wire, together with the tongue 5, into the position shown in Figure 4. In this position the ticket holds with perfect security to the fabric without the latter coming into contact with any points or even being penetrated by the material of the wire.

In the constructional form shown in Figures 5 and 6, we provide instead of the above described tongue 5 two tongues 8 and 9 situated at the outer side of the limbs 3 and 4 and which are or can be bent towards the back of the ticket in the manner shown in Figure 6. To attach the ticket to the goods the side tongues 8 and 9 are bent forwards laterally past the limbs 3 and 4 of the wire, that is to say, from the position shown in Figure 6 to a plane disposed before that plane in which the limbs 3 and 4 lie, and then the tongues 8 and 9 are turned over together with said limbs 3 and 4 of the wire down towards the back of the ticket.

Having now particularly described and ascertained the nature of our said invention, and in what manner the same is to be performed, we declare that what we claim is:

1. In a ticket for marking fabrics and the like, the combination of a ticket, a wire stirrup rigidly secured to the ticket and having two limbs projecting over the upper edge of the ticket, and a wire-portion connecting said limbs, said connecting wire portion forming a tongue which lies wholly above the upper edge of the ticket and is spaced laterally from the limbs and bendable towards the back of the ticket to form together with said limbs, a hook, said tongue

being constructed and arranged to be pushed, together with the fabric, from a plane disposed behind the limbs to a plane 45 disposed before said limbs, and afterwards to be bent down together with said limbs, over the upper edge of the ticket.

2. In a ticket for marking fabrics and the like, the combination of a ticket, a wire stirrup the ends of which are rigidly secured to the ticket, said stirrup having two substantially parallel limbs projecting over the upper edge of the ticket, and a wire-portion 55 connecting said limbs and forming tongues, which lie wholly above the upper edge of the ticket, said tongues being spaced laterally from the said limbs and bent towards the back of the ticket and being so constructed that they can be pushed from their original 60 position forwards, past the limbs, to the front of the ticket and afterwards can be bent down together with said limbs over the upper edge of the ticket in attaching the ticket to a fabric.

3. In a ticket for marking fabrics and the like, the combination of a ticket, a wire stirrup consisting of two substantially parallel limbs and a tongue-like connecting wire-portion forming together with the limbs a 70 hook, said tongue like portion lying wholly above the upper edge of the ticket and being spaced laterally from the limbs so that it can be pushed from its original position forwards to a plane disposed before the plane 75 occupied by the substantially parallel limbs, the ends of said wire stirrup having their points sunk or embedded in the material of the ticket.

In testimony whereof we affix our signatures.

WILHELM SIEGFRIED.
